WILLIAM M. CUMMISKEY, OF HONESDALE, PENNSYLVANIA, ASSIGNEE, BY MESNE ASSIGNMENTS, TO GURNEY ELECTRIC ELEVATOR COMPANY, OF HONESDALE, PENNSYLVANIA, A CORPORATION OF PENNSYLVANIA.

MOTOR CONTROL

1,122,259.

Specification of Letters Patent. Patented Dec. 29, 1914.

Application filed April 6, 1911. Serial No. 619,237.

To all whom it may concern:

Be it known that I, WILLIAM M. CUMMISKEY, a citizen of the United States, and a resident of Honesdale, in Wayne county 5 and State of Pennsylvania, United States of America, have invented certain new and useful Improvements in Motor Control, of which the following is a specification.

My invention relates to improvements in 10 systems of control for electric motors, and its object is to automatically prevent the connection of a resistance across the armature terminals of the motor unless the armature is rotating at a predetermined rate. 15 I will describe my invention in the following specification and point out the novel features thereof in the appended claims.

The drawing herewith is a diagram of 20 certain electrical apparatus and their connecting circuits.

— and — designate the mains from a suitable source of electrical supply.

10 is the shunt field winding of an electric motor which, as shown in the drawing, is 25 directly connected across these mains. 11 is the armature of this motor, and 12 and 13 are its leads or terminals.

14 is a starting resistance which is arranged to be connected in series with the 30 armature, and 15 is another resistance which is arranged to be connected across the armature or in shunt therewith in slowing down the motor.

At 20 is a manually operated switch which 35 comprises a hand lever on which is a movable contact 21 in electrical connection with the + or positive main, and stationary contacts 22, 23, 24, 25, 26 and 27, onto which the movable contact 21 may be moved.

40 30 is a solenoid which forms a part of an electromagnetically actuated reversing switch. 31 is the core of this solenoid, and 32, 33 are contact plates which are connected with but insulated from this core.

45 34 and 35 are stationary contacts which are connected with the + and — mains, respectively. To another stationary contact 36 is connected the motor armature lead 13. The stationary contact 37 is connected by 50 a conductor 16 through the resistance 14 with the other armature lead 12.

One terminal of the solenoid 30 is connected by a conductor 28 with the stationary contact 24 of the controlling switch 20,

Its other terminal is connected with the — main.

40 is another solenoid, and 41 its core. This core is mechanically geared to rotate a shaft 42 on which are a plurality of cams which are so placed on the shaft that when 50 the latter is rotated by the movement of the solenoid core 41 they will successively move switch arms or levers 43, 44, 45 and 46, against stationary contacts in their paths of movement. These switch levers are electrically connected together, and with the conductor 16, and the stationary contacts with which they coat are connected with different parts of the starting resistance 14. One terminal of the solenoid 40 is connected 70 by a conductor 47 through contacts 58 which are controlled by a contact plate 59, and with the stationary contacts 26 and 27 of the hand switch 20. Its other terminal is connected with the — main.

50 is a solenoid, and 51 its core. This, like the device before described, is arranged to rotate a cam shaft 52 and to successively move the switch levers 53, 54, 55 and 56 against stationary contacts which are connected, in this case, with different parts of the slow-down resistance 15. These switch levers are connected together and with the armature lead 12. One of the terminals of the solenoid 50 is connected with a stationary contact 64 of a controlling magnet or solenoid 60 by a conductor 57. A stationary contact 65, similar to 64, is connected by a conductor 66 through contacts 48 which are controlled by a contact plate 49 with the 90 stationary contacts 22 and 23 of switch 20. The other terminal of solenoid 50 is connected with the — main.

The controlling magnet or solenoid 60 comprises a winding 61, the terminals of 95 which are connected directly across the terminals of the motor armature 11, and a core or plunger 62 which carries a contact plate 63. This plate is arranged to be drawn up against the contacts 64 and 65 under conditions which I will specifically point out later.

When the parts are in the positions in which they are shown in the diagram the motor is at rest. Now, if an operator moves 105 the lever of hand-switch 20 to its first position to the left (indicated by the dotted line at A), the movable contact 21 will rest upon

the two stationary contacts 22 and 24. As has been shown, the contact 21 is connected with the + main. This movement of the hand-switch will then complete a circuit 5 through the conductor 28 and the solenoid winding 30 to the negative main. Solenoid 30 will then be energized and will lift the contact plates 32 and 33 up against the stationary contacts 34, 36, and 37, 35, respectively. This will complete a circuit from the + main through contacts 34, 36, conductor 13, to and through the motor armature 11, thence through conductor 12, starting resistance 14, conductor 16, and contacts 15 37, 35 to the negative main. The motor will then be started. It will be noted that bringing the contact 21 of the hand-switch upon the contact 22 will not then complete a circuit through the solenoid 50 because the low 20 resistance of the motor armature will practically short-circuit the high resistance winding 61 of the magnet 60 so that there will be no connection between its stationary contacts 63, 64. That is, the path for the 25 current from the + main through contacts 21 and 22 extends through conductors 66, contacts 48, 48, which are now bridged by the contact plate 49, to the stationary contact 65 where it ends. A further movement 30 of the hand switch lever will bring it into the position indicated by the dotted line at B. The contact 21 still remains on the contact 24, but will now also cover the stationary contact 26, and will complete a circuit 35 through conductor 47, contacts 58, 58 which are now bridged by the plate 59, to and through the solenoid winding 40, and thence to the - main. This solenoid will then be energized and will lift its core, rotating the 40 shaft 42 and closing the contacts below the switch levers 43, 44, 45 and 46 consecutively, to cut out the starting resistance 14 in a plurality of steps. The rotation of the shaft 42 is preferably retarded by a dash-pot in 45 the usual and well-known manner. The movement of the solenoid core will at the same time lift the contact plate 49 from the contacts 48. Now the armature 11 of the motor will get its current directly from the 50 source of supply and will consequently run at its full speed. In doing this it will generate a counter-electromotive force of sufficient strength to energize the winding 61 of the magnet 60, and will cause the contact 55 plate 63 to be brought into contact with and to bridge the contacts 64 and 65. When it is desired to slow-down the motor, the handle of the manually operated switch is returned to the position A. This breaks the circuit 60 through solenoid 40 so that its core will drop and lift the contact levers which it controls to reinsert the resistance 14 in the armature circuit. It will also cause the plate 49 to again bridge contact 48, 48. Now, a circuit 65 will be established from the + main through contacts 21 and 22, conductor 66, bridged contacts 48, 48, and contacts 65, 64 which are now bridged by the plate 63, conductor 57 to and through solenoid 50, and to the - main. The solenoid core 51 will then be 70 raised and will break the circuit of solenoid 40 by lifting the plate 59 from the contacts 58, 58. It will also close the contact lever 53 against its stationary contact, and this will result in connecting all of the resistance 15 75 across or in shunt with the motor armature. The rotation of the latter in its magnetic field will cause it to generate a current through this resistance 15, thus putting a considerable load upon the motor and causing it to slow down. Further upward movement of the solenoid core 51 will cause the contact lever 54 to close against its contact, short-circuiting a part of the resistance 15, 80 and thus increasing the load upon the armature. Similarly, the levers 55 and 56 will short-circuit more of the resistance 15 in two more steps, causing the motor to run very slowly. The rotation of the cam shaft 52 is 85 also preferably retarded by a dash-pot. 90

It may be seen that if when at any time the lever of the manually operated switch 20 is moved back to its A position, the motor armature is rotating too slowly to maintain the core 62 in magnet 60 in its raised position, the solenoid 50 which controls the slow-down resistance 15, cannot be energized. Also, if, during the slow-down operation described, the motor loses enough of its 95 speed to cause the core 62 to drop, the circuit through solenoid 50 will be broken, and the contact levers which it controls raised to disconnect the slow-down resistance 15. Obviously, the electromotive force generated by the motor armature, must be considerably 100 greater to cause the core 62 to be raised than it need be to maintain it in its raised position. It is also to be noted that the resistance 15 cannot be connected across the armature until the resistance 14 is connected in 105 series with it, because of the arrangement of the contacts 48, 48 and the contact plate 49 which breaks the circuit of the solenoid 50 whenever the plunger of the solenoid 40 is raised. The solenoid 40 is also made inoperative whenever the core of the solenoid 50 is raised because the circuit of the solenoid 40 is broken whenever the contact plate 59 is raised from the stationary contacts 58, 58. When the lever of hand switch 20 110 is brought back to its central position the circuits through solenoids 30 and 50 are broken. The contact plates 32 and 33 will drop, thereby cutting off the current supply from the motor armature so that it will 115 come to rest. 120

If a brake is used in conjunction with the motor it may be released by the energization of a solenoid 70 which has a conductor 71 leading to a stationary contact 38 in posi- 125 130

tion to be connected with the + main when the contact plate 32 is raised, and has another conductor 72 leading to the - main. Similar operations to those described may

5 take place when the lever of the manually operated switch is moved to the right. But in this case a magnet 30^A of the reversing switch will raise contact plates 32^A and 33^A against certain stationary contacts which are 10 so connected to the mains and with the motor armature as to cause the current in the latter to flow in the opposite direction so that its direction of rotation will be reversed.

15 What I claim is.—

1. An electric motor having an armature, a starting resistance, a circuit closer for said starting resistance, a slow-down resistance arranged to be connected across the 20 armature, a circuit closer for said slow-down resistance, and means for rendering, said circuit closer for the slow-down resistance automatically dependent upon both the speed of the motor armature and upon the 25 position of the circuit closer for the starting resistance.

2. An electric motor having an armature, a resistance, manually controlled means for connecting said resistance across the armature, and means automatically actuated by the rotation of the armature for controlling 30 said manually controlled means.

3. An electric motor having an armature, a resistance, a circuit closer arranged to 35 connect said resistance across the armature, and an electroresponsive device independent of said circuit closer automatically controlled by the rotation of the armature for controlling the circuit closer.

40 4. An electric motor having an armature, a resistance, a circuit closer arranged to connect said resistance across the armature, an actuating device for the circuit closer, and an electroresponsive device connected 45 across the armature and arranged to render said actuating device inoperative except when the motor is running above a predetermined rate of speed.

5. An electric motor having an armature, 50 a resistance, a circuit closer arranged to connect said resistance across the armature, an electromagnet for actuating the circuit closer, a circuit for said magnet, a manually operated switch, and an electromagnetically 55 actuated switch in the magnet circuit, said electromagnetically actuated switch being arranged to be actuated by the rotation of the motor armature.

6. An electric motor having an armature, 60 a resistance, a circuit closer having a plurality of switch arms for connecting different amounts of said resistance across the armature, an electromagnet for actuating the circuit closer, a circuit for said magnet, 65 a manually operated switch, and an auto-

matic switch in the magnet circuit, said automatic switch comprising an electromagnet connected across the motor armature.

7. An electric motor having an armature, a resistance, a circuit closer arranged to 70 connect said resistance across the armature, a manually operated switch for controlling the motor, said switch having a full-speed and an intermediate slow-speed position, said intermediate position being arranged 75 to control the resistance circuit closer, and automatic means for rendering the resistance circuit closer inoperative, except when the motor armature is rotating above a predetermined rate of speed.

8. An electric motor having an armature, a starting resistance arranged to be connected in series with the armature, a circuit closer for said starting resistance; a slow-down resistance arranged to be connected across the armature, a circuit closer for said slow-down resistance; a manually operated switch for controlling both of said circuit closers, said switch having a full speed position for controlling the starting 80 resistance circuit closer, and an intermediate slow speed position for controlling the slow-down resistance circuit closer; and automatic means for rendering the slow-down resistance circuit closer inoperative while said manually operated switch is being moved into its full speed position.

9. An electric motor having an armature, a starting resistance arranged to be connected in series with the armature, a circuit 90 closer arranged to cut out said starting resistance in a plurality of steps; a slow-down resistance arranged to be connected across the armature, a circuit closer arranged to connect different amounts of slow-down resistance across the armature; a manually 105 operated switch for controlling both of said circuit closers, said switch having a full-speed position for controlling the starting resistance circuit closer, and an intermediate slow speed position for controlling the slow-down resistance circuit closer, and automatic means for rendering the slow-down resistance closer inoperative when said 110 manually operated switch is being moved into its full-speed position.

10. An electric motor having an armature, a starting resistance arranged to be connected in series with the armature, a circuit closer for said starting resistance; a 120 slow-down resistance arranged to be connected across the armature, a circuit closer for said slow-down resistance; a manually operated switch for controlling both of said circuit closers, said switch having a full- 125 speed position for controlling the starting resistance circuit closer, and an intermediate slow-speed position for controlling the slow-down resistance circuit closer, automatic means for rendering the slow-down 130

- 4
- resistance circuit closer inoperative when said manually operated switch is being moved into its full-speed position, and other means for rendering the slow-down resistance circuit closer inoperative when the starting resistance circuit closer is closed. 5
11. An electric motor having an armature, a starting resistance arranged to be connected in series with the armature, a circuit closer for said starting resistance; a slow-down resistance arranged to be connected across the armature, a circuit closer for said slow-down resistance; a manually operated switch for controlling both of said circuit closers, said switch having a full-speed position for controlling the starting resistance circuit closer, and an intermediate slow-speed position for controlling the slow-down resistance circuit closer, automatic means 10 for rendering the slow-down resistance circuit closer inoperative when said manually operated switch is being moved into its full-speed position, and other means for rendering the starting resistance circuit closer inoperative when the slow-down resistance circuit closer is closed. 15
12. An electric motor having an armature, a starting resistance arranged to be connected in series with the armature, a circuit closer for said starting resistance; a slow-down resistance arranged to be connected across the armature, a circuit closer for said slow-down resistance; a manually operated switch for controlling both of said circuit closers, said switch having a full-speed position for controlling the starting resistance circuit closer, and an intermediate slow-speed position for controlling the slow-down resistance circuit closer, automatic means 20 for rendering the slow-down resistance circuit closer inoperative when said manually operated switch is being moved into its full-speed position, and other means for rendering the starting resistance circuit closer inoperative when the slow-down resistance circuit closer is closed. 25
13. An electric motor having an armature, a starting resistance arranged to be connected in series with the armature, a circuit closer for said starting resistance; a slow-down resistance arranged to be connected across the armature, a circuit closer for said slow-down resistance; a manually operated switch for controlling both of said circuit closers, said switch having a full-speed position for controlling the starting resistance circuit closer, and an intermediate slow-speed position for controlling the slow-down resistance circuit closer, automatic means 30 for rendering the slow-down resistance circuit closer inoperative when said manually operated switch is being moved into its full-speed position, and other means for rendering the starting resistance circuit closer inoperative when the slow-down resistance circuit closer is closed. 35
14. An electric motor having an armature, a starting resistance, a circuit closer for said starting resistance, a slow-down resistance arranged to be connected across the armature, a circuit closer for the slow-down resistance, electro-responsive means for actuating the circuit closer for the slow-down resistance, a control switch dependent upon the speed of the motor armature, and means 35 for rendering said electro-responsive means automatically dependent upon said control switch and upon the circuit closer for the starting resistance. 40
15. An electric motor having an armature, a starting resistance, a circuit closer for said starting resistance, a slow-down resistance arranged to be connected across the armature, a circuit closer for the slow-down resistance, electro-responsive means for actuating the circuit closer for the slow-down resistance, a control switch dependent upon the speed of the motor armature, and means 45 for rendering said electro-responsive means automatically dependent upon said control switch and upon the circuit closer for the starting resistance. 50
16. 13. A motor having an armature, a starting resistance arranged to be connected in series with the armature, a circuit closer arranged to cut out said starting resistance in a plurality of steps, an actuating magnet therefor; a slow-down resistance, a circuit closer arranged to connect different amounts of said slow-down resistance across the armature in a plurality of steps, an actuating magnet therefor; circuits for both of said actuating magnets, a manually operated switch for controlling the circuits, said switch having a full-speed position for controlling the starting resistance circuit closer, and an intermediate position for controlling the slow-down resistance circuit closer; 55 means controlled by the slow-down resistance circuit closer actuating magnet for breaking the circuit of the starting resistance circuit closer actuating magnet when the slow-down resistance circuit closer is closed; means for breaking the circuit of the slow-down resistance circuit closer actuating magnet when the starting resistance circuit closer is closed; and an automatic switch in the slow-down resistance circuit closer actuating magnet circuit arranged to prevent the closing of said circuit except when the motor armature is rotating above a predetermined rate of speed, said automatic switch comprising an electromagnet 60 connected across the motor armature. 65
17. An electric motor having an armature, a starting resistance, a circuit closer for said starting resistance, a slow-down resistance arranged to be connected across the armature, a circuit closer for the slow-down resistance, electro-responsive means for actuating the circuit closer for the slow-down resistance, a control switch dependent upon the speed of the motor armature, and means 70 for rendering said electro-responsive means automatically dependent upon said control switch and upon the circuit closer for the starting resistance. 75
